ATTORNEY

UNITED STATES PATENT OFFICE.

BENJAMIN GROSS, OF NEW YORK, N. Y., ASSIGNOR TO BENJAMIN & EDWARD J. GROSS CO., INC., OF NEW YORK, N. Y.

DESIGN FOR A FINGER RING OR ARTICLE OF SIMILAR NATURE.

Application filed October 24, 1928. Serial No. 28,613. Term of patent 14 years.

To all whom it may concern:

Be it known that I, BENJAMIN GROSS, a citizen of the United States, residing at New York city, in the county and State of New York, have invented a new, original, and ornamental Design for a Finger Ring, or Article of Similar Nature, of which the following is a specification; reference being had to the accompanying drawing forming a part thereof.

The figure is a perspective view of a finger ring showing my new design.

I claim:

The ornamental design for a finger ring or article of similar nature, as shown.

In testimony whereof I affix my signature.

BENJAMIN GROSS.
